UNITED STATES PATENT OFFICE

168,012

COMBINED SWING SEAT AND SUPPORTS
THEREFOR

Franklyn York, Plymouth, Mich., assignor to Marmy Products Company, Birmingham, Mich.,
a corporation of Michigan

Application September 6, 1951, Serial No. 16,524

Term of patent 14 years

(Cl. D34—15)

To all whom it may concern:

Be it known that I, Franklyn York, a citizen of the United States, residing at Plymouth, in the county of Wayne and State of Michigan, have invented a new, original, and ornamental Design for a Combined Swing Seat and Supports Therefor, of which the following is a specification, reference being had to the accompanying drawings forming part hereof.

Fig. 1 is a perspective view of a combined swing seat and supports therefor showing my new design; and

Fig. 2 is a front elevational view thereof, to a reduced scale.

The side of the swinging toy not shown in Fig. 1 is identical with the side thereof which is shown.

I claim:

The ornamental design for a combined swing seat and supports therefor, substantially as shown and described.

FRANKLYN YORK.
